UNITED STATES PATENT OFFICE.

OSCAR PRYIBIL, OF ST. LOUIS, MISSOURI.

DESIGN FOR A POOL-TABLE.

SPECIFICATION forming part of Design No. 33,713, dated December 11, 1900.

Application filed November 16, 1900. Serial No. 36,781. Term of patent 7 years.

To all whom it may concern:

Be it known that I, OSCAR PRYIBIL, a citizen of the United States, residing at the city of St. Louis, in the State of Missouri, have invented and produced a new and original Design for a Pool-Table, of which the following is a full, clear, and exact description, reference being had to the accompanying drawing, forming part of this specification.

10 The drawing is a perspective view showing my new design.

As shown in the drawing, the leading or material feature of my design consists of an octagon body 1 of a pool-table, with a border-

15 molding 2 around its upper edge, on the inside of which is a round surface 3, cut away at intervals, as shown at 4. Appearing in the sides of the body 1 opposite the cut-away portions 4 are panel-like portions 5. The body is supported on legs 6. 20

I claim as my invention—

The design for a pool-table herein shown and described.

OSCAR PRYIBIL.
